UNITED STATES PATENT OFFICE.

JOHANNES IHLEFELDT, OF DESSAU, GERMANY, ASSIGNOR TO THE FIRM G. POLYSIUS,
OF DESSAU, GERMANY.

ROTARY MILL.

Application filed August 31, 1926, Serial No. 132,742, and in Germany September 1, 1925.

My invention relates to an improved rotary mill provided with a plurality of chambers and working with intermediate sifting. More especially, the invention resides therein, that bearing ledges are provided in the sifting chambers located between the individual grinding chambers, said ledges serving for the reception of individual sieves; another feature resides therein that 10 said sieves are attached to the said ledges by means of screws, bolts or the like. In order to render possible removing the sieves from the outside a plurality of the holding means mentioned is arranged in apertures, 15 such as slots or the like, provided in the closing covers of the mill, the arrangement being such that two sieves may be drawn out through a feed aperture after the respective cover with its bolt has been removed.

20 The invention is illustrated diagrammatically and by way of example on the accompanying drawing on which

Fig. 1 is a cross section through the mill, and

25 Fig. 2 a section through the sifting chamber.

The sifting chamber C which is located between two grinding chambers A and B carries on the inner surface of the walls a plurality of stationary ledges d formed, for instance, by pieces of angle iron or the like, their number corresponding with that of the sieves f. There are provided, in the example shown, eight sieves f in the sifting chamber 30 C of the mill, and arranged practically side by side. The sieves form in this example obtuse angles, the sifting chambers being, therefore, polygonal, but the shape of the sieves may be such that a sifting chamber 35 of circular section is obtained. The sieves f are retained in proper position by the ledges d of a suitable section, as well as by screw bolts g, the heads h of which press the

45 rims of the sieves f upon said ledges d, as shown in the figures. Each sieve is supported by two ledges. Some of the bolts g are connected with, and carried by, a cover i closing an aperture k and being affixed to the mill casing by screws or the like. When the screw or the like has been removed, the 50 respective cover i can be removed from the respective aperture and the adjacent sieve or sieves may be removed from the mill.

Owing to the particular construction of 55 the mill, as shown and described, one holding device is required for two sieves, but, on the other hand, only four apertures are required for removing eight sieves from out of the mill. The other bolts, that is to say, 60 those located between the apertures need only be screwed off the ledges d, when the sieves can be withdrawn also from the intermediate ledges cooperating with the just mentioned bolts.

Fig. 1 shows how a sieve f¹ is just being 65 removed from the drum, and also the neighbouring sieve f² may be removed instantaneously thereafter in the same manner.

I claim:

A multi-chamber mill comprising grinding compartments and an intermediate sifting compartment, said sifting compartment being provided with a series of circularly arranged ledges, sifter sections seated upon 70 said ledges, clamping devices operative from the exterior of the mill wall for holding the sections upon said ledges, the mill wall of 75 said sifter compartment being provided with openings one for each pair of sifter sections through which each pair of sections 80 may be removed from the mill and closure means for said openings.

In testimony whereof I affix my signature.

JOHANNES IHLEFELDT.
